(57) CLAIM

The ornamental design for a football mailbox, as shown and described.

DESCRIPTION

FIG. 1 is a perspective view of the instant invention; FIG. 2 is a front view thereof; FIG. 3 is a left side view thereof, said left side view depicting the mailbox front cover in a raised position; FIG. 4 is a right side view thereof; FIG. 5 is a rear view thereof; FIG. 6 is a top view thereof; and, FIG. 7 is a bottom view thereof.

The broken line showing of the face mask in FIG. 3 is for illustrative purposes only and forms no part of the claimed design.
